R. H. WELLES,
ELECTRIC SEARCH LAMP,
APPLICATION FILED JAN. 4, 1915.

1,171,488.

Patented Feb. 15, 1916.

UNITED STATES PATENT OFFICE.

RICHARD H. WELLES, OF KENOSHA, WISCONSIN, ASSIGNOR TO THE BADGER BRASS MFG. CO., OF KENOSHA, WISCONSIN, A CORPORATION OF WISCONSIN.

ELECTRIC SEARCH-LAMP.

1,171,488.

Specification of Letters Patent. Patented Feb. 15, 1916.

Application filed January 4, 1915. Serial No. 319.

To all whom it may concern:

Be it known that I, RICHARD H. WELLES, a citizen of the United States, residing at the city of Kenosha, in the county of Kenosha and State of Wisconsin, have invented certain new and useful Improvements in Electric Search-Lamps, of which the following is a specification.

My invention relates to improvements in electric search lamps and, although adaptable for various types of lamps, is particularly well fitted for use in the construction of head-lamps on vehicles.

In the drawings which accompany this application I have illustrated a bicycle head-lamp embodying my invention, and in said drawings Figure 1 is a vertical axial section taken through the center of the lamp; Fig. 2 is a fragmentary plan view of Fig. 1, certain parts being broken away to show the details of the construction; Fig. 3 is a section taken on the line 3—3 of Fig. 2; Fig. 4 is a plan view of the connector; Fig. 5 is an axial section taken through the connector on the line 5—5 of Fig. 4; Fig. 6 is a transverse section through the connector, taken on the line 6—6 of Fig. 5; Fig. 7 is an end elevation of Fig. 4, looking from the right-hand of said figure; and Fig. 8 is a fragmentary elevation of the lower part of Fig. 1.

During recent years the electric lighting of road vehicles has been introduced and has made marvelous progress. The progress made has resulted in the design and development of a vast number of electrical appliances, lamps, etc., in use on automobiles, bicycles, etc.; but until recently, such devices have not been originated or manufactured with such attention to detail, efficiency and economy as have similar devices employed in other of the electrical arts. However, competition in the lamp business has reached such a point that in order to obtain a market for lighting equipment, the manufacturer must produce an article which is extremely practical and efficient in operation and comparatively graceful in appearance which can be sold at cut-rate prices and still obtain a fair margin of profit. Heretofore many electrical head-lamps have been designed and manufactured without great attention to economy in the number of parts or in the use of materials; others, while being extremely cheap to manufacture, have been so clumsy or unpractical as to be very

unsatisfactory when used under the severe conditions of bad weather, dirt, and vibration encountered when operating road vehicles.

The object of my invention is to produce an electric head-lamp which is of exceptionally rugged and substantial design, capable of being manufactured with great ease and economy, while at the same time the lamp is of graceful appearance, practical, and extremely convenient and easy to operate and keep in repair. The construction illustrated involves the elimination of a large number of parts necessary in prior art constructions of this general character, and results in a corresponding economy in manufacture and reliability in operation.

In the drawings I have shown my invention applied to a bicycle head-lamp of the parabolic type. In the lamp illustrated, the main casing 10 is formed from a single piece of brass or other suitable metal, and comprises a bowl substantially parabolic in shape which is flared outwardly at 11 at the glazing end of the lamp, and at the rear end 75 of the bowl, centrally of the axis thereof, there is formed an integral tubular rearwardly projecting extension 12 large enough to accommodate the plug or connector 13. In the front of the casing 10, intermediate 80 the flaring front and the bowl, I prefer to shape, either by a spinning process or by means of suitable dies, an annular outwardly facing seat 14 which is adapted to support the parabolic reflector 15, the inner end of 85 which is flanged, as shown at 16, to engage said seat. The circular glazing 17, which closes the outer end of the reflector 15, is forced into intimate contact with the annular flange of the latter, and similarly said 90 flange is forced into engagement with its seat support 14 by means of a non-continuous locking ring 18 made of relatively stiff resilient wire and seated within an annular 95 inwardly facing groove 19 formed in the metal of the outwardly flared continuation 100 of the bowl of the outer casing. The outer bowl-shaped casing 10 and the inner reflector 15 are symmetrical in shape and nested co-axially together, and the inner reflector 15 is made with a rearwardly projecting integral tubular extension 20, in its 105 general shape similar to the extension 12 of the outer casing and co-axial therewith. This extension 20 constitutes a support for 110

- the "Ediswan" base 21 of the lamp bulb 22, which projects inwardly within the bowl of the reflector and is provided with the customary tungsten filament 23 arranged substantially in the focal point of said reflector. 5
- The lamp as a whole is supported on the vehicle by means of a clamp 24, which may be of any suitable type admitting of easy and quick adjustment.
- 10 Describing first the connector, this includes a main body portion of hard rubber composition or similar material, the inner end 25 of which is a smooth cylinder adapted to slide freely within the tubular extension 12, the outer projecting portion 26 of said connector being also cylindrical in shape, but slightly larger in diameter and knurled on its exterior to permit it to be grasped with ease by means of the fingers when occasion 15 arises to remove or adjust the connector. The lamp bulb illustrated is of the single filament type, both of the two terminals of which are insulated from the base of the lamp casing, making it necessary to equip 20 the connector and lamp base with two sets of contacts. Hence, in the connector I drill or mold a pair of longitudinal apertures extending the length of the connector, parallel with and spaced apart from the axis of the 25 body portion. In each of these longitudinal apertures 27 there is tightly driven or molded *in situ* a cylindrical rod 28, one end of which is substantially flush with the inner end of the connector and is bored out 30 longitudinally from the inner end to accommodate a plunger 29 between the annular head 30 of which and the end of the bore is interposed a spiral spring 31 which tends to force said flanged plunger outwardly. 35
- 40 The end of the bore in said rod 28 is crimped over slightly so as to reduce its diameter at the end to prevent the plunger 29 from being thrown out and lost, the outer end of said plunger being correspondingly reduced 45 in diameter. In the inner end of each of the rods 28 I drill a transverse terminal hole 32 large enough to admit the end of a suitable electrical conducting wire which is clamped by means of a small axially disposed screw 33 threaded into the outer end of the rod 28. The screws 33 may be adjusted by means of a small screw driver inserted in the outer ends of the longitudinal bores 27 and the conducting wires can be 50 inserted in said transverse holes 32 of the rods 28 through a pair of transverse apertures 34 drilled in the outer portion 26 of the connector in proper position to register with the transverse holes 32 in said connector rods 28. Substantially midway of 55 the length of the reduced cylindrical portion 25 of the connector there is driven transversely and diametrically through the center thereof a small pin 35 long enough 60 to project a short distance out of the part 25 at both of its ends. This pin 35 passes through the bores 27 without contacting with the connector rods 28, and the axis thereof forms substantially a right-angle with a line connecting the centers of the said 70 rods.
- Referring to the lamp bulb proper, this, as heretofore referred to, is furnished with an "Ediswan" base, this base comprising an insulating filler 36 surrounded by a cylindrical metallic casing 37 and provided with a pair of diametrically opposite contact plates 38 which project slightly from the outer end of the base and are connected to the ends of the tungsten filament within 80 the lamp bulb. These contact plates on their opposite edges are shaped substantially to conform with the curvature of the central insulating filler 36, and on their adjacent edges have a somewhat similar curvature, each of the plates spanning approximately one-quarter of the circumference of the base. Adjacent the end of the tubular metallic casing 37 of the base is secured in position a transverse diametrically 85 extending pin 39 somewhat similar to the pin 35, and also arranged in such position that a plane extending axially of the lamp base and in which the axis of said pin is located, substantially bisects and is at right-angles to a line connecting the centers of 90 said contact plates 38.
- Referring to Fig. 2, it will be noticed that in the end of the tubular extension 12 I form a pair of diametrically opposed and 100 longitudinally extending slots 40, the inner end of each of which terminates in slots 41 and 42 extending circumferentially for a similar distance around the tube 12. All of these slots 40, 41 and 42 are wide enough to 105 admit the ends of the pin 35 and the connector 13, and the opposite ends of the slots 41 and 42 are also cut out, as shown in Fig. 2, in order to furnish small pockets 43 and 43^a to accommodate the ends of said pin 35, 110 and adapted to prevent rotary movement of said connector when the pin 35 is located in either set of said pockets. It is manifest that a slight inward endwise movement of the connector 13 will permit the ends of 115 the pin 35 to disengage the pockets with which they may be in engagement, and the connector may then be rotated to bring the ends of the pin 35 into register with the longitudinally extending slots 40, in which position the connector may be withdrawn; or 120 the rotary movement of the connector may be continued so as to bring the ends of the pin 35 into engagement with the pockets in the opposite ends of the slots 42. It 125 should be noted that the slots 41 and 42 are of such length that lines drawn diametrically across the tube 12 connecting the pockets 43 and 43^a are substantially at right-angles to each other so that the connector 130

13 has two permanent positions at right-angles to each other besides its midway position which permits it to be withdrawn from the tube 12. In the tubular extension 20 5 extending rearwardly from the reflector 15, there is cut a pair of longitudinally extending opposed slots 44, similar to the slots 40, but having their open ends at the inner end of said tubular extension 20 so as to permit 10 the entrance of the ends of the pins 39 when the bulb is inserted. The outer ends of these slots 44 are extended in either direction around the circumference of the tube 20 so as to form pairs of pockets 45 and 46, 15 the centers of which are spaced apart ninety degrees around the circumference of the tube. These sets of pockets 45 and 46 are of suitable shape to accommodate the ends of the pin 39 and to prevent movement of 20 the base when the ends of the pin 39 are seated in said pockets. It should be noted also that the pockets 45, as shown, are offset longitudinally slightly with reference to the pockets 46 so as to permit of a slight 25 longitudinal adjustment of the bulb axially of the reflector by rotating it through an angle of ninety degrees and thus changing the location of the seating pin 39 from one set of said pockets to the other set. 30 It is manifest that the dimensions of the various parts of the lamp structure are such that when the connector and lamp base are seated in their respective socket tubes, the plunger pins 29 engage the outer end of the 35 base of the bulb and are pushed longitudinally within the connector a sufficient amount to insure a positive contact with the plates 38 when the latter are in proper register with said pins. 40 Referring to Figs. 1 and 8, it will be noticed that at the bottom of the outer casing there is formed in the seat 14 by means of a suitable punch a pointed projection 47 which enters a small notch 48 cut out of the 45 periphery of the flange 16 of the reflector. This insures that the reflector 15 will always be supported in the casing in the same angular position, and this position is such that the pockets 43 are in alinement with the 50 pockets 46. This being the case, it is clear that when the connector-pin 35 is placed in the pockets 43 and the lamp base is located in position such that the pin 39 is seated within the pockets 46, the plunger pins 29 55 will engage the contact plates 38 and the lamp will be energized. If, however, the connector be turned in an anti-clockwise direction through an angle of ninety degrees so that the pin 35 becomes seated in the 60 pockets 43^a, the ends of the plunger 29 will then be moved into positions such that they engage the exposed portion of the insulating filler 36 between the contact plates 38 and do not touch the plates 38, and thus in this 65 latter position the circuit through the lamp

will be broken. It is manifest that if I desire to change the focal position of the filament axially of the reflector by moving the lamp bulb through an angle of ninety degrees so that the pin 39 becomes seated 70 within the pockets 45, the switching function of the connector member is not destroyed, since in this position the on and off positions of the connector will be simply reversed.

It is apparent that the locking plungers 29, although carried by the connector, serve as locking members for the base of the lamp as well as for the connector. In this connection it should be noted that the pockets, 80 43, 43^a are cut in the outer edge of the connector socket slot, while the pockets 45 and 46 are cut in the inner edge of the slots in the extension 20, the spring-pressed plungers thus maintaining the connector-pin 35 in 85 engagement with the pockets 43 or 43^a, and also at the same time maintaining the base of the lamp in position in the inner socket 20 by virtue of the ends of the pin 39 being forced into engagement with the pockets 45 90 or 46 in the inner tubular extension 20. In addition to the above described double acting function of the plungers 29 as locking means for both the base of the lamp and for the connector, these pins 29 also render 95 unnecessary any troublesome flexible electrical conductors for making the connection between the base of the lamp and the outer connector.

It will be apparent from the above description that I have provided an extremely simple and compact search lamp which is constructed of a comparatively small number of parts, and those of simple and substantial design. No wires or adjustable connections are used within the lamp and no 100 external switch or cut-out is necessary. The supports for the connector and the socket, being made integrally with the casing and the reflector, cannot be loosened up or become lost; and, in general, the design of 110 the lamp is such as to permit of its being manufactured at an extremely low cost.

Although I have illustrated the preferred embodiment of my invention as applied to 115 a lamp of this particular type, yet it should be understood that many of the structural details may be modified considerably without departing from the spirit of the invention, and hence, I do not wish to be limited, 120 except as specified in the appended claims.

I claim—

1. In an electric lamp, the combination of an outer casing provided with a tubular socket adapted to form a support for an 125 electric connector, an inner reflector seated within said casing and having a separate tubular socket adapted to register with said first socket and adapted to form a support for a lamp projecting within said reflector, 130

4
a connector supported independently of said second socket projecting outwardly from said first socket and provided with resilient contact means on its inner end, and a lamp seated within said inner socket and provided with a contact member on its outer base portion adapted to engage said resilient contact means.

2. In an electric search lamp, the combination of an outer bowl-shaped casing provided with an integral tubular socket portion, a bowl-shaped reflector nested within said outer bowl and provided with an integral tubular socket portion co-axial with said first extension, an electrical cylindric plug connector detachably supported coaxially in said outer socket, and a lamp bulb provided with a base detachably supported within said reflector extending through said inner socket and adapted directly to engage said connector.

3. In an electric search lamp, the combination of an outer bowl-shaped casing provided at its base with a tubular extension 25 projecting from and co-axial with the bowl, an inner bowl-shaped reflector nested within said outer casing and provided with an outwardly projecting tubular rear extension co-axial with and disconnected from said 30 first extension, an electrical connector plug detachably supported in said outer extension, a connection extending through said plug and provided at its inner end with a resilient contact, a lamp bulb within said 35 reflector and provided with a base extending through said inner tube, and a contact plate on said base adapted directly to engage said resilient contact member.

4. In an electric search lamp, the combination of an outer bowl-shaped casing provided with a tubular socket, a reflector nested within said outer casing and provided with a tubular socket substantially co-axial with said outer socket, said outer socket being 45 provided with a T-shaped slot open at its outer end, a cylindrical plug of resilient material provided with a transverse pin projecting from said cylinder and adapted to enter said T-shaped slot, a resilient eccentrically disposed contact member on the inner end of said plug and provided with an electrical connection extending through said plug, an electric bulb contained within said reflector and provided with a base supported 50 within said inner socket, and a contact eccentrically mounted on the rear end of said base adapted to engage said resilient contact member, the ends of the lateral arms of said T-shaped slot being suitably spaced 55 around the circumference of said outer socket to provide an on and off position for said contact.

5. In an electric search lamp, the combination of an outer bowl-shaped casing provided with a tubular socket portion having

a T-shaped slot in its circumference open at its outer end, an inner reflector seated within said outer casing and provided with a tubular socket portion registering and co-axial with said outer socket, an electric bulb 70 within said reflector and provided with a cylindrical base supported within said inner socket, said inner socket and base being provided with mutual interlocking engagement whereby said base may be rotated through 75 an angle of substantially ninety degrees within said socket, the socket when in either of said extreme angular positions being located at different longitudinal positions within said socket, a cylindrical plug of insulating material supported within said outer socket and having a locking pin adapted 80 to enter said T-shaped slot, an electrical connection extending through said plug and provided with a resilient post contact at its 85 inner end, said post contact being eccentrically mounted in the inner end of said plug, said plug being adapted to be adjusted by means of said pin in said T-shaped slot in two distinct locking positions ninety 90 degrees apart from each other, an electric bulb contained within said reflector and provided with a resilient base adapted to be adjusted in two positions within said inner socket ninety degrees apart from each other, 95 and a contact on the outer end of said base adapted to engage and register with said resilient post member when said base and said connector are in relatively the same angular position, and adapted to be out of 100 contact when said base and connector are in different angular positions.

6. In an electric lamp, the combination of an outer casing provided with a bayonet socket, an inner reflector nested within said outer casing and provided with an inner bayonet socket co-axial with said outer socket, a lamp bulb within said reflector and provided with an "Ediswan" base adapted to be supported within said inner socket, 105 an outer connector provided with an "Ediswan" base extending and supported within said outer socket, and a resilient connection interposed between the adjacent ends of said "Ediswan" bases whereby the lamp and connector are locked in position.

7. In an electric lamp, the combination of an outer casing provided with a bayonet socket, an inner reflector nested within said outer casing and provided with an inner bayonet socket co-axial with said outer socket, a lamp bulb within said reflector and provided with an "Ediswan" base adapted to be supported within said inner socket, an outer connector provided with an "Ediswan" extension extending and supported within said outer casing, a resilient contact plunger, and an electric conductor extending from said plunger outwardly 120 through said connector.

8. In an electric search lamp, the combination of an outer casing, an inner parabolic reflector provided with a tubular socket co-axial with the reflector, said socket being provided with a T-shaped bayonet slot, the pin seats at the lateral arms of the T being longitudinally offset with reference to each other, a lamp-bulb provided with a filament adapted to be located substantially at the focal point of said reflector and provided with an "Ediswan" base supported in said inner socket and adapted to be adjusted with its locking pin in either of said seats whereby the filament may be placed in two longitudinal positions co-axial with the reflector, a connector supported in said outer casing, and a resilient contact member interposed between said connector and said base where-
- 5 10 15 20 25 30
- by said base is locked in position and the lamp is energized.
9. The combination of a casing, provided with axially-aligned bayonet sockets open at their opposite ends for the admission of a pair of electrical conducting devices, each having inter-locking bayonet connection with its respective bayonet socket, and a resilient contact member carried by one of said conducting devices whereby said devices are locked in position in said sockets and an electric connection is established between them.
